CLAIM

The ornamental design for a vehicle glass, as shown and described.

DESCRIPTION

FIG. 1 is a top, front, right-side perspective view of vehicle glass;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a top, front, right-side perspective view shown with a vehicle for environmental context.

The dashed broken lines depict portions of the vehicle glass that form no part of the claimed design. The dashed broken lines showing the vehicle in FIG. 8 is provided for environmental context and forms no part of the claimed design.

1 Claim, 8 Drawing Sheets
